CLAIM

The ornamental design for the drug delivery implement with translucent housing, as shown and described.

DESCRIPTION

FIG. 1 is a perspective view of an ornamental design for a drug delivery implement with translucent housing showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a perspective view of FIG. 1 with a cap separated from the drug delivery implement.

1 Claim, 5 Drawing Sheets---
